DESIGN FOR A FINGER RING MOUNTING

David Pfeffer, New York, N. Y.

Application September 17, 1946, Serial No. 133,365

Term of patent 3½ years

(Cl. D45—10)

To all whom it may concern:

Be it known that I, David Pfeffer, a citizen of the United States, and a resident of 2190 Boston Road, county of Bronx, city and State of New York, have invented a new, original, and ornamental Design for a Finger Ring Mounting, of which the following is a specification, reference being had to the accompanying drawing, forming a part thereof.

On the drawing:

Figure 1 is an enlarged fragmentary perspective view showing the setting element of a finger ring mounting, embodying my new design.

Figure 2 is a top plan view of the finger ring mounting.

Figure 3 is a side elevational view thereof.

I claim:

The ornamental design for a finger ring mounting, as shown.

DAVID PFEFFER.
